UNITED STATES PATENT OFFICE

109,928

DESIGN FOR A BOTTLE

Charles A. Williams, Winthrop, Mass., assignor to C. M. Kimball Company, Everett, Mass., a corporation of Massachusetts

Application April 6, 1938, Serial No. 76,325

Term of patent 7 years

To all whom it may concern:

Be it known that I, Charles A. Williams, a citizen of the United States, residing at Winthrop, in the county of Suffolk and State of Massachusetts, have invented a new, original, and ornamental Design for a Bottle, of which the following is a specification, reference being had to the accompanying drawing, forming a part thereof.

In the drawing the figure is a perspective view of a bottle showing my new design.

I claim:

The ornamental design for a bottle substantially as shown.

CHARLES A. WILLIAMS.
